[57] CLAIM

The ornamental design for wrapping paper for confectionery, as shown and described.

DESCRIPTION

FIG. 1 is a top plan view of the first embodiment of the wrapping paper for confectionery embodying my design;

FIG. 2 is a bottom plan view thereof;

FIG. 3 is a front elevational view thereof, shown in a filled state;

FIG. 4 is a rear elevational view thereof, shown in a filled state;

FIG. 5 is a right side elevational view thereof, shown in a filled state;

FIG. 6 is a left side elevational view thereof, shown in a filled state;

FIG. 7 is a top plan view of the second embodiment of the wrapping paper for confectionery embodying my designs;

FIG. 8 is a bottom plan view thereof;

FIG. 9 is a front elevational view thereof, shown in a filled state;

FIG. 10 is a rear elevational view thereof, shown in a filled state;

FIG. 11 is a right side elevational view thereof, shown in a filled state; and,

FIG. 12 is a left side elevational view thereof, shown in a filled state.

The broken lines shown in FIGS. 7, 8, 9, 10 and 12 are for illustrative purposes only and form no part of the second embodiment.
